CLAIM

The ornamental design for a fitness and therapeutic roller, as shown and described.

DESCRIPTION

FIG. 1 is a right front perspective view of a fitness and therapeutic roller;

FIG. 2 is a top plan view of the fitness and therapeutic roller of FIG. 1, the bottom plan view and the front and rear elevation views are all identical thereto; and,

FIG. 3 is a left side elevation view of the fitness and therapeutic roller in FIG. 1, the right side elevation view is identical thereto.

The fitness and therapeutic roller of the present design is depicted in a “broken away” manner. The appearance of any portion of the article between the break lines forms no part of the claimed design. The broken lines depicting portions of the fitness and therapeutic roller are for illustrative purposes only and form no part of the claimed design.

1 Claim, 3 Drawing Sheets(56)
